SWIVEL BARRICADE STRUCTURE WITH ATTACHED SUPPORTS

Augustus J. Penote, Shaker Heights, Ohio

Application September 24, 1932, Serial No. 634,639

Renewed September 14, 1934

6 Claims. (Cl. 256—64)

This invention relates particularly to improvements in swivel barricade structure with attached supports, and especially to such structures which may be assembled to hold in horizontal position one or more bars or rails to be mounted in streets or roadways to guard excavations or various incomplete engineering work, by barring passage of unauthorized parties across such barricade structure.

10 My barricade structure is designed to hold the ends of rails or bars in overlapping relation, and to further include lateral sockets for receiving the ends of various supporting tubes or bars therein detachably, so that a plurality of barricade units or series thereof may, when not in use for the purpose of guarding engineering or kindred work, be disassembled for convenience in storage or transportation.

15 A further object of my invention is the provision of connecting mechanism for bars or rails, which mechanism may include metal holders positioned in axial alignment in superposed relation for relative rotation and having a vertical pivot bolt connecting ends of the holders, each 20 of the latter having horizontal openings therethrough for receiving the ends of barricade rails therein, so that the overlapping ends of cross bars will be inserted in openings in different planes, and may swing on their pivot.

25 A still further object of my invention is the provision of lateral sockets extending outwardly from and integral with each of said holders forming two pairs, or one pair for each holder, these sockets being inclined to the vertical axis 30 of the holder, those in the lower holder being adapted to receive legs therein thereby forming a yoke, and the upper sockets for receiving therein signal bars separating as they rise for obvious reasons.

35 It is a further object to adapt my swivel structure of superposed pivotal holders, all of which are closed end holders, to sets of holders including more than a single pair, so that even three or more superposed holders may receive therein 40 a corresponding number of rail ends to thereby affect a very serviceable temporary continuous fencing all of whose connections are pivotal.

45 With these and other objects in view my invention consists in certain details of construction to be described, claimed, and illustrated in the accompanying drawings, in which,—

50 Figure 1 is an end elevation of a lower holder and supports, with an upper holder swung to a slightly different plane;

55 Figure 2 is a side elevation of a barricade of overlapping rails;

60 Figure 3 is a side elevation of a double swivel structure of closed end metal links provided with lateral sockets, certain details being shown in section;

65 Figure 4 is a central vertical section of a barricade link;

70 Figure 5 is a side elevation of an intermediate link with parts broken away;

75 Figure 6 is a perspective view of three superposed links enclosing the ends of barricade members;

80 Figure 7 is a perspective of swivel barricade link holders receiving the ends of horizontal barricade members for protecting an excavation;

85 Figure 8 is a side elevation of a modified form of swivel links in sectional detail;

90 Figure 9 is a sectional detail view of a modified socket for a barricade holder with securing means for a supporting device;

95 Figure 10 is a sectional detail view of a further modification of securing means for a socket, and

100 Figure 11 is a sectional view of a modified form of clamp socket for a supporting device.

105 In my invention as embodied in the present drawings, I provide one of the closed end holders of my swivel structures with external sockets 9 inclined outwardly, as shown in Figs. 1, 2, 3, 6 110 and 7, from the closed holder 8, to receive therein supporting legs 5, while the holding links 3 receive in their horizontal openings the ends of horizontal barricade rails or bars 6 held therein by the closed ends 7 of such links, the links 3 of a pair of holders 8 being pivoted together at their contacting ends by a bolt 21, as shown clearly in Fig. 1.

115 The tubular inclined sockets 9 are usually cast integral with the holder 8, as shown in Fig. 1, 40 while the holders of a pair are directed oppositely in a vertical direction, when it is convenient to use the inclined sockets 9 of the lower holder for the supporting legs, and the upper inclined sockets for any other convenient purpose, such as holding 45 rods 13 for warning flags 19 or lights 20.

120 As shown in the first three views, the end of a holder 8 which is opposite the sockets 9 will be provided with an opening 22 in the longitudinal axis of the holder for receiving the bolt 21 to 50 permit swinging of the bars 6 on such vertical pivot bolts. In some instances it may be desirable to use such a closed end holder 23 having a pivot opening 22 at either end thereof. Different structures may be used for such holders to 55

secure the legs 5 in the inclined sockets. As for example, such sockets may be threaded as shown at 26 in Fig. 3 for this purpose; or the sockets 17 as shown in the holders of Fig. 8, may be provided with an integral shoulder 16 to limit the inward movement of the legs. This structure is also made use of in Figs. 4, 9, 10 and 11, to hold the legs in the sockets.

The structure above described having the 10 superposed hollow holders or links pivoted for rocking movement on the vertical bolts 21, is further adapted for use of more than two superposed bars or rails, especially where temporary barricade construction is desired, as shown in 15 Fig. 6. In this form there is indicated a lower and an uppermost holder 25 pivoted to the ends of an intermediate holder or link 16 which is provided with openings 22 at both ends, but as shown in Fig. 5, not provided with leg supporting 20 sockets.

It will be evident that any number of intermediate links 16 may be pivoted together on a longitudinal axis and to the socketed holders 25, shown in Fig. 6, thus building up temporary fencing to any reasonable height desired.

The swivel arrangement of the holders is especially advantageous in the opportunity afforded of swinging the rails or bars of different planes upon vertical pivots to different angles, as may be desired. In Fig. 2, the rails of different sections lie in substantially identical planes, but the rails shown in Figs. 6 and 7 are shown in widely different planes to provide sections of superposed rails directed at angles to each other, so that an enclosure of the sections may be the result.

It is to be further noted as evident that a builder or a general construction contractor, may advantageously keep in stock a number of units adapted for the upper and lower links 25, and also hold in readiness any number of intermediate links 16 all of which may be assembled in superposition in the order desired, all of such links having closed ends except that small openings 22 are provided for attaching the links pivotally by the bolts 21, as before explained. The ends of the rails 6 in all cases will be inserted lengthwise in the proper links in order of engagement in building up the barricade required.

The endwise insertion of the rail ends into the links of appropriate size and shape to receive them affords very positive bracing of the swivel holders by the cross rails, even though the rail sections are mounted at an angle to each other. A tight connection at the corner of an extended barricade will therefore result. In the first seven views, the inclined sockets 9 are provided a short distance from the adjacent end of the holder with which they are integral; but in Figs. 8, 10 and 11, the sockets 17 are extended beyond the adjacent end, as shown clearly in Fig. 8. The same structure is used in the upper link 25 of the latter view, thereby providing a shoulder upon which a supporting loop 26 may be hung for supporting the light 20.

The construction illustrated in Fig. 8, provides smooth inner surfaces for the sockets 17 and, the weight of the holder unit upon the lower sockets tends to urge the legs 5 into them. The form of socket shown in Fig. 9 however, provides a screw 12 for rigidly securing the legs 5 in the sockets.

Figs. 10 and 11 disclose further modified forms of attachment of the legs in the sockets; the socket in the former structure having a protuberance 15 within which and the leg itself, a

notch 27 is provided for receiving therein a cross pin or bolt 16 to temporarily hold the latter as well as the leg in position. This socket shown in Fig. 11 takes in part the form of a clamp 13 to be tightened together about the upper portion of the leg 5 by insertion of a bolt 28 and securing such clamp ears 13 by external nut 14, as shown.

In any of these forms of pivoted holders, both the lower and upper ends of each holder 8, 10 or 25, will be closed so that the insertion of an end of an horizontal rail or bar will serve to hold the supporting legs 5 in substantially vertical position, the closed upper end 7 binding upon the upper surface of the rail end to avoid undesired tipping of the barricade out of the erect position. It will be understood, in view of the relative and more or less varied means proposed for such superposed construction, that a strong and linearly extended barricade structure as shown in Fig. 2 may be used and laterally extended to any proposed distance, and that each section of the barricade may be built from a single rail, or that two or more holders may be used as suggested in Figs. 1, 3, 6, or 8.

In operation of assembly, in whatever direction the sections will extend from the pivoted holders, it is wise to mount the several sections from one rail to the next at first.

The ends of the rails of such sections are mounted in overlapping relation by inserting the 30 ends in the open sides of the holders which, by the vertical pivots, may be swung at an angle to each other, and such continuation of the sections by the swiveled holders being so arranged that the sections may form an enclosure such as shown 35 in Fig. 7, or may be arranged to make use of more than four sections, depending upon the contour of the obstacles to be enclosed. These closed end holders avoid undesired tipping of the sections lengthwise of the rails, as will be understood 40 from the showing in Fig. 7.

It will be understood that the utilization of swivel joints of superposed closed end holders having more than two holder units, provide feasible mounting of three or more section rails in the 45 manner shown in Fig. 6, to avoid entrance of parties within the enclosure, as of live stock, the several sections being readily dismounted by lengthwise withdrawal of the rail ends from the side openings of the upper holder of a given joint, 50 and continuing such withdrawal, one at a time until but one rail remains in each section. All such changes in the upbuilding of the several sections may be made, at the same time retaining the continued barricade its full length. In all 55 swivel joints contemplated in the present structure, both vertical ends of all holders or links thereof, are closed to engage the longitudinal edges of the rail ends inserted in such holders, and thereby maintain the leg supports erect in 60 position.

Having described my invention, what I now claim and desire to secure by Letters Patent, is:—

1. In a barricade structure of the class described, a leg-supported holder unit comprising 65 open metal holders having closed ends, one holder being fixed upon the legs and the other pivotally mounted upon the fixed holder.

2. In a barricade structure, a series of leg-supported holder units comprising a plurality of 70 superposed elongated open holders end to end for receiving therein the ends of connecting barricade rails in overlapping relation, the uppermost holder of said series having closed ends and the lowermost holder having closed ends and includ- 75

ing a vertical pivot connecting its upper end with the uppermost holder, and having divergent and integral sockets for receiving therein the supporting legs for the unit, and means for detachably securing the legs in said sockets.

5. 3. A barricade support comprising an open metal body member forming two upwardly converging legs having their upper ends fixedly connected with said member, and a separate open 10 metallic closed end holder pivotally mounted upon said body member thereby forming a swivel holder unit for receiving therein the overlapping ends of barricade rails.

15. 4. In a barricade structure, the combination of a series of leg-supported holder units, each comprising a plurality of closed end superposed open side holders for receiving therein the ends of connecting bars lengthwise of the latter, and at least one of said units comprising closed end holders pivoted one upon another for relative rotation 20 about a vertical axis.

20. 5. In a barricade structure, a plural bar holder unit comprising an elongated closed metal frame having a side opening adapted to receive an end

of a barricade rail therein and formed of a metal body member having integral therewith two upwardly converging and spaced apart inclined sockets, and tubes fixedly insertable in said sockets for supporting legs, the tubes and sockets having 5 registering cross notches forming a tubular opening therein, and a securing bolt insertable in said cross notches for securing the tubes in the sockets, and a closed end holder pivoted vertically upon said metal frame for receiving in said side opening the end of an overlapping rail by endwise insertion.

6. A barricade support comprising a closed end metal open body member for receiving a barricade rail therein and having divergent sockets 15 integral with said body member, for receiving the upper ends of upwardly converging supporting legs, the said sockets comprising yieldably separable lugs having aligned openings therein, and a cross bolt insertable in said openings and having 20 means for tightening said bolt and thereby clamping said lugs together to secure said legs in the sockets.

AUGUSTUS J. PENOTE.
